UNITED STATES PATENT OFFICE.

WILLIAM P. FELL, OF HURON, SOUTH DAKOTA.

REIN-GUARD.

No. 849,467.

Specification of Letters Patent.

Patented April 9, 1907.

Application filed February 14, 1906. Serial No. 301,000.

To all whom it may concern:

Be it known that I, WILLIAM P. FELL, a citizen of the United States, and a resident of Huron, in the county of Beadle and State of 5 South Dakota, have invented a new and Improved Rein-Guard, of which the following is a full, clear, and exact description.

My invention relates to an improvement in rein-guards designed to prevent the reins 10 from becoming caught or entangled with the wagon-pole.

The object of my invention is to provide a device of this character at a very small cost which will be simple and durable and which 15 may be quickly and easily applied to various sizes and types of wagons.

A further object of my invention is to provide a device of this character which will have a limited horizontal movement with the 20 neck-yoke as the latter oscillates, but which will be secured against becoming detached when in use and will not work up and down on the wagon-pole, but will be securely held in noiseless engagement therewith.

With the above-mentioned objects in view 25 I have shown in the accompanying drawings the construction of a device embodying the principles of my invention, in which similar characters of reference indicate corresponding parts in both figures.

Figure 1 is a perspective view of a wagon-pole with its neck-yoke and having my invention applied thereto; and Fig. 2 is a plan view of a slight modification thereof, showing in dotted lines a position which the guard 35 may assume.

Referring now to the drawings in detail, 1 represents an ordinary wagon-pole, of wood or metal, and 2 a neck-yoke of appropriate 40 length and diameter. The pole is preferably provided with a bracket 3 to limit the longitudinal movement of a ring 4, which fits loosely over the pole and which is secured to the neck-yoke by suitable hooks or staples 5.

45 The construction so far specified is merely illustrative of a common form of wagon-pole and neck-yoke and forms no part of my invention. In actual usage of the construction so far specified great inconvenience and

50 often danger is encountered by the cross-reins becoming entangled with the end of the pole, as will be readily understood. Now, therefore, I have devised a novel rein-guard mechanism adapted for use with this common type of pole and neck-yoke, which comprises a bow-shaped piece of stiff metal wire

or rod 6, the extremities of which are secured near the ends of the neck-yoke by suitable hooks or staples 7, as shown in Fig. 1, or merely by the ends of this wire being bent to 60 form loops which snugly fit the extremities of the neck-yoke, as shown at 8 in Fig. 2, the purpose being to secure the ends of this wire 6 to the neck-yoke near each end thereof in a simple and reliable manner. The central 65 portion of this bow-shaped member 6 is loosely mounted upon the pole 1 in such a manner that it may have a limited horizontal rocking movement when the neck-yoke is similarly moved, as shown by dotted lines in 70 Fig. 2, but also in such a manner as to prevent any vertical movement with relation to the end of the pole. A convenient means for accomplishing this result may be by employing a socketed cap-piece preferably 75 formed of resilient metallic wire, the spring-socket being of such a diameter that it may be easily sprung over the end of the pole, as shown at 9. This spring-socket is provided with an eye or loop 10 on its outer end, in 80 which loosely works the central part of the bow-shaped wire 6, as clearly shown in both figures.

Obviously other forms of well-known spring-caps may be substituted for the one 85 illustrated without departing from the spirit of my invention, the essential requirements being a convenient means to position the member 6, which may be easily and securely retained on the pole end and quickly detached 90 therefrom, if desired. It will be seen that by the coaction of the resilient cap-piece 9 with the resilient bow-shaped member 6 the reins will be guarded and the free longitudinal play of the neck-yoke be permitted. 95

I am aware that it has been proposed to provide a curved guard-rod attached at its rear ends to a neck-yoke and to be positioned centrally by being secured to a wagon-pole in order to prevent reins from being entangled by said pole, and I do not claim such an arrangement broadly. 100

Having thus described my invention, I claim as new and desire to secure by Letters Patent— 105

1. The combination with a vehicle-pole and a neck-yoke held to slide and rock thereon, of a resilient bow-piece having its ends mounted upon the neck-yoke near the respective ends of said neck-yoke, and a resilient connection between the bow-piece and the end of the pole. 110

2. The combination with a vehicle-pole, a neck-yoke, and means for holding the neck-yoke rockably and slidably mounted upon the pole near its outer end, of a resilient cap-piece mounted upon said end of the pole, and a resilient bow-piece or rein-guard loosely mounted near its center upon the cap-piece, the ends of the bow-piece having engagement with respective end portions of the neck-yoke.

3. The combination with a vehicle-pole, a neck-yoke, an elongated looped bracket on the pole near its outer end, a ring loosely mounted on the pole within the bracket, and means for loosely securing the ring on the neck-yoke at its center, of a resilient cap-piece formed of coiled spring-wire and mounted upon said outer end of the pole, said cap-piece having an eye formed on its outer end, and a resilient bow-piece of metal rod forming a rein-guard, said bow-piece loosely engaging the eye near the center of said bow-piece, and rings on the ends of the

bow-piece and mounted on the respective ends of the neck-yoke.

4. A rein-guard, comprising a bow-shaped rod having loops or eyes at its ends to receive the ends of a neck-yoke, and a cap adapted to fit on the end of a wagon-pole and provided with an eye or loop through which the rod passes.

5. A rein-guard, comprising a resilient bow-shaped rod having loops or eyes at its end to receive the ends of a neck-yoke, and a cap adapted to fit upon the end of a wagon-pole and provided with an eye through which the rod passes, the said cap being formed of resilient wire.

In testimony whereof I have signed my name to this specification in the presence of two subscribing witnesses.

WILLIAM P. FELL.
